GRINDING MACHINE

Wallace H. Wood, Worcester, Mass., assignor to
Norton Company, Worcester, Mass., a corpora-
tion of Massachusetts

Application October 26, 1940, Serial No. 362,898

7 Claims. (Cl. 51—95)

The invention relates to grinding machines, and more particularly to a hydraulically operated grinding wheel feeding mechanism.

One object of the invention is to provide a simple and thoroughly practical hydraulically operated cylindrical grinding machine. Another object of the invention is to provide a hydraulically operated grinding wheel feeding mechanism. A further object of the invention is to provide a hydraulically operated single vane type motor driven wheel feeding mechanism. A further object of the invention is to provide a control mechanism for a hydraulic motor wheel feeding mechanism which may be actuated continuously for a plunge-cut operation or intermittently in timed relation with the table reciprocating movement for a traverse grinding operation.

A further object of the invention is to provide a combined selector and speed control valve for a hydraulic feed motor whereby the motor may be actuated either continuously or intermittently and whereby the speed of the motor may be varied either during continuous or intermittent operation. A further object of the invention is to provide a hydraulically operated wheel feeding mechanism including a vane type fluid motor which may be controlled by one of two different control valves which may be selected by means of a manually operable selector valve whereby either a continuous feed may be obtained for a plunge-cut grinding operation or an intermittent feed at the ends of the table stroke for a traverse grinding operation may be readily obtained. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the drawings, in which is shown one of various possible embodiments of the mechanical features of this invention,

Fig. 1 is a front elevation of the improved grinding machine;

Fig. 2 is a cross-sectional view through the grinding machine wheel feeding mechanism, showing the wheel slide and headstock in elevation;

Fig. 3 is a diagrammatic view, showing the hydraulic wheel feed control mechanism together with the piping arrangement;

Fig. 4 is a vertical sectional view, on an en-

larged scale, through the fluid motor for actuating the wheel feed and also through the control valve mechanism therefor;

Fig. 5 is a cross-sectional view, taken approximately on the line 5—5 of Fig. 4;

Fig. 6 is a sectional view, taken approximately on the line 6—6 of Fig. 4; and

Fig. 7 is a diagrammatic view, taken approximately on the line 7—7 of Fig. 4.

A grinding machine embodying this invention has been illustrated in the drawings, comprising a base 10 which supports a longitudinally movable work supporting table 11 on a V-way 12 and a flat way 13 for a longitudinal reciprocatory movement relative to the base 10. A headstock 14 and a footstock 15 are mounted on the table 11 and are arranged rotatably to support a cylindrical work piece 16 in operative relation with a rotatable grinding wheel 17. The grinding wheel 17 is rotatably supported on a transversely movable wheel slide of the usual and well known type, such as that shown in the expired U. S. patent to Norton, No. 762,838 dated June 14, 1904. In the preferred form, an electric motor 20 is mounted on the wheel slide 18. The motor 20 is provided with a pulley 21 which is connected by a driving belt 22 with a pulley 23 mounted on the end of a wheel spindle 24. The wheel spindle 24 serves as a support for the rotatable grinding wheel 17.

A fluid pressure mechanism may be provided for reciprocating the work table 11. As illustrated in the drawings, a cylinder 30 is fixedly mounted to the under side of the table 11. The cylinder 30 contains a piston (not shown) which is connected by a pair of hollow piston rods 32 and 33 with a pair of hollow brackets 34 and 35 which are fixedly mounted on opposite ends of the base 10.

In the preferred construction the base 10 is formed as a hollow box-like construction in which the lower portion serves as a reservoir 38. Fluid is drawn from the reservoir 38 through a pipe 39 by means of a motor driven fluid pump 40 and is forced through a pipe 41 to a table control valve 42. A fluid pressure relief valve 43 is provided in the pipe 41 so as to allow excess fluid under pressure within the system to return directly to the reservoir 38, thus maintaining a desired and predetermined pressure within the fluid system. The details of construction of the table control valve 42 together with the connections to the cylinder 30 have not been illustrated in detail in the present application since they are not considered to be a part of the present invention,

The table reciprocating mechanism is substantially identical with that shown in my prior U. S. Patent No. 2,071,677 dated February 23, 1937, to which reference may be had for details of disclosure not contained herein.

A manually operable control lever 44 is provided for actuating the control valve 42. The lever 44 serves, as in my prior patent, to actuate a stop and start valve (not shown) and by rotation of the knob 45, the normal speed of the table 11 may be readily controlled as desired. The control valve unit 42 also contains a reversing valve which is arranged to be actuated automatically by means of a table reversing lever 46. The lever 46 is pivotally supported on a stud 47 on the base 10 of the machine. A pair of adjustable table dogs 48 and 49 are adjustably supported in a T-slot 50 formed in the front edge of the table 11. The dogs 48 and 49 are arranged successively to engage and shift the reversing lever 46 so as to control the length of the reciprocating stroke of the table 11.

The table 11 may be traversed longitudinally by means of a manually operable traverse wheel 51 when desired. The manually operable traversing mechanism has not been illustrated in detail herein since it is not considered to be a part of the present invention. The table traversing mechanism is identical with that shown in my prior U. S. Patent No. 2,071,677 above referred to, to which reference may be had for details of disclosure not contained herein.

A wheel feeding mechanism is provided for feeding the wheel slide 18 together with the grinding wheel 17 transversely relative to the base 10 on the usual V-way and flat way (not shown). A depending half nut 55 depends from the under side of the wheel slide 18. The half nut 55 meshes with or engages a rotatable cross feed screw 56 which is rotatably journaled in bearings 57 and 58. The bearings 57 and 58 are mounted in fixed relation with the base 10. The left-hand end of the feed screw 56 is slidably keyed within a sleeve 59 which is in turn fixedly mounted on a shaft 60. The left-hand end of the shaft 60 is journaled in a bearing 61. A gear 62 is mounted on the outer end of the shaft 60 and meshes with a pinion 63 formed on the inner end of a sleeve 64. The sleeve 64 is rotatably supported on a fixed stud 65 which is mounted in fixed relation with the base 10 of the machine. A ratchet wheel 66 is formed integral with the sleeve 64. A manually operable hand wheel 67 is also rotatably supported on the stud 65 and is drivingly connected to rotate the sleeve 64 when desired.

It will be readily apparent from the foregoing disclosure that when the manually operable feed wheel 67 is rotated, a rotary motion will be imparted through the sleeve 64, the pinion 63, the gear 62, the shaft 60, the sleeve 59, to rotate the feed screw 56 which in turn transmits a transverse movement through the half nut 55 to the wheel slide 18 and grinding wheel 17. The direction of rotation of the manually operable feed wheel 67 determines the direction of rotation of the feed screw 56 and also the direction of transverse movement of the wheel slide 18 and the grinding wheel 17.

In order to feed the grinding wheel transversely for a grinding operation, it is desirable to provide a power actuated feed which may be either operated continuously for a plunge-cut grinding operation or may be actuated intermittently and automatically at the ends of the

work table stroke for a traverse grinding operation.

An oscillatable arm 68 is rotatably supported on the periphery of the sleeve 64. The arm 68 serves as a support for a feed pawl 69 which is pivotally supported by a stud 70 to the arm 68. It will be readily apparent from the foregoing disclosure that if the arm 68 is oscillated, the ratchet pawl 69 engaging the teeth of the ratchet wheel 66 will rotate the feed screw and thereby impart a transverse feeding movement to the grinding wheel slide 18 and the grinding wheel 17 to feed it toward the work axis to grind the work piece to the desired and predetermined extent. The oscillatable arm 68 is connected by means of a stud 71 to the upper end of a link 72. An adjustable rotatable crank plate 73 is fixedly supported on a shaft 74. The crank plate 73 is provided with a radially extending T-shaped slot 75 in which fits the head 76 of a bolt 77. The bolt 77 in turn supports a sleeve 78. The outer end of the bolt 78 is provided with a screw thread 79 on which fits a manually adjustable nut 80. The periphery of the sleeve 78 fits within a bearing surface 81 formed in the lower end of the link 72. In the position of the parts as shown in Fig. 4, it will be readily apparent that if the shaft 74 is oscillated, a rotary motion will be imparted to the crank plate 73 to impart a crank motion to the bolt 77 and the sleeve 78 which in turn transmits a vertical motion to the link 72, thereby oscillating the pawl supporting arm 68 to produce a desired and predetermined feeding movement of the wheel slide 18 and the grinding wheel 17.

The extent of oscillation of the feed pawl 69 may be readily varied by adjusting the eccentricity of the bolt 77 and sleeve 78. As shown in Fig. 4, the bolt and sleeve 78 are positioned to impart a maximum oscillatory stroke through the link 72 to the pawl carrying arm 68. If it is desired to decrease the amount of feeding movement imparted for each actuation of the crank plate 63, the nut 80 is loosened and the bolt 77 together with the sleeve 78 is moved upwardly so that the bolt head 76 moves upwardly within the T-slot 75 (Fig. 4). During this movement the axis of the bolt 77 and sleeve 78 approaches the axis of the shaft 74.

The axis of the bolt 77 and sleeve 78 is moved into a position to coincide with the axis of the shaft 74; then no oscillatory movement will be imparted to the feed pawl 69. It will be readily apparent that the extent of feed from the maximum, as shown in Fig. 4, to the minimum may be obtained by adjusting the position of the bolt 77, after which it may be readily locked in adjusted position by tightening the clamping nut 80.

It is desirable to provide a power actuated mechanism for oscillating the crank plate 73 either continuously for providing a plunge-cut feed during a plunge-cut grinding operation or intermittently in timed relation with the reciprocation of the work table 11 so that the wheel may be fed at the ends of the table stroke during a traverse grinding operation.

In the preferred construction, a fluid pressure mechanism is provided for actuating the feeding mechanism, comprising a fluid motor 85 which is preferably of a single vane type having a circular chamber 86. A rotor 87 is provided within the chamber 86. The rotor 87 is preferably formed as an integral part of the shaft 74. The rotor shaft 74 is rotatably supported in bearings 88, 89

and 90 formed in the casing 91. A single vane 92 is fixedly mounted on the rotor 87 and is arranged to travel through an arcuate path of approximately 270 degrees as fluid under pressure is admitted either to one side or the other thereof. A baffle plate 93 is fixedly mounted within the chamber 86 and serves to form two motor chambers, namely, the motor chamber 86 and a motor chamber 94 on the other side of the vane 92. The motor 85 is connected by pipes or passages 95 and 96 with a reversing valve 97. The reversing valve 97 is a shuttle type valve comprising a plurality of valve pistons 98, 99 and 100. The reversing valve 97 is provided with end chambers 101 and 102 so that it may be readily shifted from one end to the other by means of fluid under pressure.

The vane 92 of the fluid motor 85 (Fig. 5) is shown at the end of its circular path of movement in a clockwise direction. The vane 92 in Fig. 4 is shown in a midway position. In Figs. 3 and 7 the vane 92 is shown as approaching the end of its stroke in a counterclockwise direction, that is, with the fluid pressure passing into the motor chamber 94.

In the position of the parts as shown in Fig. 3, fluid under pressure from the motor-driven pump 48 passes through a pipe 103 to a selector and speed control valve 104. This valve 104 has been shown diagrammatically in Fig. 3 as comprising three sectional portions 104, 104a and 104b to show clearly the passages and ports contained therein. The valve 104 is a rotary type selector valve, the function of which will be further described hereinafter. This valve comprises a valve rotor 105. The valve rotor 105 is arranged so that fluid under pressure passing through the pipe 103 may pass through the passage 106 and through a pipe 107 and a pipe 108 into a valve chamber 109 located between the valve pistons 98 and 99 and through the passage 95 into the fluid motor chamber 94 to move the vane 92 in a counterclockwise direction.

In order automatically to control the reversing valve for providing a continuous infeeding movement for a plunge-cut grinding operation, a pilot valve 110 is provided; or for providing an intermittent operation of the fluid motor in timed relation with the table movement, a pilot valve 111 is provided. The pilot valve 110 is a piston type valve comprising valve pistons 112, 113 and 114 forming valve chambers 115 and 116 therebetween. The valve 110 is operatively connected so that it may be shifted by and in timed relation with the rotary movement of the fluid motor vane 92.

A downwardly extending arm 117 is fixedly mounted on a slide bar 118 which is supported in guides 119 and 120 formed in the motor and valve casing. The opposite ends of the slide rod 118 are connected by arms 121 and 122 with the valve pistons 114 and 112, respectively. The downwardly extending arm 117 is arranged in the path of a pair of V-shaped arms 123 and 124 which are fixedly mounted on the motor shaft 74. The arms 123 and 124 are provided with actuating screws 125 and 126, respectively, which are arranged to engage the downwardly extending arm 117 of the valve 110 so as to shift the valve first in one direction and then in the other to control the admission of fluid under pressure to the opposite end chambers 101 and 102 of the reversing valve, thus automatically and continuously causing an oscillatory movement of the motor vane 92 to be imparted to the feed pawl 69 to 75

provide a plunge-cut feeding movement of the grinding wheel 17. In the position as shown in Fig. 3, fluid under pressure in the pipe 107 passes through a pipe 128 to the valve chamber 115 of the valve 110 and passes out through a pipe 129 and through a valve chamber 130 in the valve 104. From the valve chamber 130 fluid passes through a pipe or passage 131 into the end chamber 101 of the reversing valve 97 to move the reversing valve into its extreme right-hand end position (Fig. 3).

During the movement of the reversing valve toward the right, fluid may exhaust from the reversing valve end chamber 102 through a pipe 132, through a valve chamber 133 in the valve 104, and out through a pipe 134, through the valve chamber 116 of the pilot valve 110, and out through an exhaust pipe 135 which returns exhaust fluid to the reservoir 38. It will be readily apparent from the foregoing disclosure that when the valve 104 is in the position illustrated in Fig. 3, the pilot valve 110 will be rendered operative so that movement of the rotary vane 92 of the motor 85 will control the movement of the pilot valve 110 so as to provide a continuous oscillating movement of the fluid motor vane 92 which is in turn imparted to produce a continuous oscillation of the feed pawl 69, thereby producing a plunge-cut infeeding movement of the grinding wheel 17.

The pilot valve 111 is also a piston type valve comprising valve pistons 138, 139 and 140 which are arranged to form valve chambers 141 and 142. The valve 111 is provided with a valve stem 143 which is connected by a stud 144 with one end of a link 145. The other end of the link 145 is pivotally connected to a downwardly extending arm 146 (Fig. 1) which is operatively connected to move with the reversing lever 46. It will be readily apparent from the foregoing disclosure that each time the reversing lever 46 is actuated by the table dogs 48 and 49, a shifting movement will be imparted through the link 145 to shift the pilot valve 111.

When it is desired to provide a traverse grinding feed, that is, an intermittent infeeding of the grinding wheel 17 at the ends of the reciprocating stroke of the table 11, the valve rotor 105 is rotated ninety degrees (Fig. 3), in which position fluid under pressure from the pipe 103 passes through the passage 106a and through the pipe 108 to the reversing valve 97. In this position of the selector valve 104, fluid under pressure passing through the pipe 107 passes through a pipe 150, into the valve chamber 141 of the valve 111, and passes out through a pipe 151 and through the valve chamber 130, and out through the pipe 131 into the end chamber 101 of the reversing valve 97 to move the valve pistons 98, 99 and 100 toward the right (Fig. 3). During this movement, fluid under pressure within the chamber 102 is exhausted through the pipe 132, through the valve chamber 133 in the valve 104, out through a pipe 152, into the valve chamber 142 of the valve 111, and out through an exhaust pipe 153 which connects with the exhaust pipe 135 to convey exhaust fluid to the reservoir 38.

Similarly, when the reversing lever 46 is engaged by the table dog 48 to shift the reversing lever 46 in a clockwise direction, the valve pistons 138, 139 and 140 of the valve 111 are shifted into their extreme left-hand position so that fluid under pressure within the pipe 150 enters the valve chamber 142 in the valve 111 and

passes through the pipe 152, through the valve chamber 133, the pipe 132, into the end chamber 102 of the reversing valve 97 to move the valve pistons 98, 99 and 100 toward the left (Fig. 3), which movement shifts the valve into a reverse position. In the left-hand end position of the valve 97, fluid under pressure passing through the pipe 108 enters the valve chamber 109a located between the valve pistons 99 and 100 and passes outwardly through the passage 96 into the fluid motor chamber 86 to impart a clockwise movement to the motor vane 92, which movement is imparted through the crank plate 73 above described to impart an oscillatory movement to the feed pawl 69. During the 15 clockwise movement of the vane 92, fluid is exhausted from the motor chamber 94, through the passage 95, and out through an exhaust pipe 154 which connects with the exhaust pipe 135 to convey exhausting fluid to the reservoir 38.

It will be readily apparent from the foregoing disclosure that each time the reversing lever 46 is shifted at the ends of the table stroke, a shifting movement will be imparted to the valve 111 to shift the reversing valve 97 and thereby impart 25 an oscillatory movement to the motor vane 92 which in turn imparts a corresponding oscillating movement to the feed pawl 69.

It is desirable to provide a readily accessible means for rendering operative either the pilot valve 110 or the pilot valve 111. A control knob 155 located on the front of the machine base 10 is mounted on the end of a rotatable shaft 156. The shaft 156 carries a gear 157 (Fig. 6) which meshes with a gear 158 mounted on the end of a rotatable shaft 159. The shaft 159 is provided with a spiral gear 160 (Fig. 6) which meshes with a spiral gear 161 (Fig. 5) which is fixedly mounted on the left-hand end of the rotor 105 of the selector valve 104. It will be readily apparent from the foregoing disclosure that a slight rotary movement of the knob 155 on the front of the machine base will be imparted to rotate the rotor 105 of the selector valve 104 so as to render operative either the pilot valve 110 to provide a continuous infeed of the grinding wheel for a plunge-cut operation or to render operative the pilot valve 111 so that an intermittent infeeding movement is obtained at the end of the reciprocating stroke of the table 11 for a traverse 50 grinding operation.

The operation of this improved feeding mechanism will be readily apparent from the foregoing disclosure. Assuming the parts to have been previously adjusted, a work piece 16 is placed in operative position in the machine and the lever 44 is shifted to start the flow of fluid in a traverse grinding operation if desired, and the knob 155 is shifted into the traverse grinding position so as to render the pilot valve 111 operative to control the reversing valve 97 in timed relation with the shifting of the reversing lever 46 to impart an intermittent feeding movement of the grinding wheel at the end of the table stroke. The bolt 71 and sleeve 78 are adjusted relative to the axis of the shaft 74 and crank plate 73 so that the desired oscillating movement will be imparted to the feed pawl 69 at each actuation of the motor vane 92. If a plunge-cut grinding operation is desired, the knob 155 is shifted to render the pilot valve 110 operative so that it controls the shifting movement of the reversing valve 97. The pilot valve 110 being automatically shifted by and in timed relation with the oscillating movement of the motor vane 92, will pro-

vide an automatic continuous oscillation of the motor vane 92 which in turn will impart a continuous oscillation of the feed pawl 69 in the manner above described to provide a continuous infeeding movement of the grinding wheel for a plunge-cut grinding operation.

The passages 106 and 106a in the rotor 105 of the combined selector and speed control valve 104 serves as throttling means whereby fluid under pressure conveyed to the motor 85 may be varied as desired to vary the speed of the feeding movement of the grinding wheel 17 either during a continuous plunge-cut grinding operation or during an intermittent traverse grinding operation.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine having a longitudinally movable table, a rotatable work support thereon and a transversely movable rotatable grinding wheel, means to reciprocate said work table longitudinally, a wheel feeding mechanism operatively connected to move said wheel transversely, a fluid motor to actuate said feeding mechanism, a reversing valve to change the direction of movement of said motor, a pair of independent pilot valves each operatively connected to shift said reversing valve in either direction, operative connections between the table reciprocating mechanism and one of the pilot valves whereby the reversing valve and the motor may be actuated to produce an infeeding movement of the grinding wheel intermittently at the ends of the table stroke, operative connections between the second pilot valve and the fluid motor whereby the motor actuates the second pilot valve continuously to produce a continuous infeed or plunge-cut, and a selector valve whereby one of the pilot valves may be rendered operative while the other remains inoperative.

2. In a grinding machine having a longitudinally movable rotatable work support and a transversely movable rotatable grinding wheel, means including a reversing lever to reciprocate said work support longitudinally, a wheel feeding mechanism operatively connected to move the grinding wheel transversely, a vane type fluid motor to actuate said feeding mechanism, a reversing valve operatively connected to control the direction of movement of said motor, a pair of independent pilot valves, operative connections between each of the pilot valves and the opposite ends of said reversing valve whereby either of the pilot valves may be utilized to actuate said reversing valve, operative connections between the table reversing lever and one of said pilot valves whereby the reversing valve and the fluid motor may be actuated intermittently to produce an infeeding movement of the grinding wheel at the ends of the work table stroke, operative connections between the second pilot valve and the fluid motor vane whereby the motor actuates the second pilot valve continuously to produce a plunge-cut feed of the grinding wheel, and a selector valve whereby either of said pilot valves may be rendered operative to control said motor,

3. In a grinding machine having a longitudinally movable rotatable work support and a transversely movable rotatable grinding wheel, means including a reversing lever to reciprocate said work support longitudinally, a wheel feeding mechanism including a nut and screw operatively connected to move said wheel transversely, a pawl and ratchet to rotate said screw, a vane-type fluid motor to oscillate said pawl, a reversing valve associated with said motor, a pair of independent pilot valves each of which is operatively connected to actuate said reversing valve, operative connections between the table reversing lever and one of said pilot valves whereby the pilot valve, the reversing valve and the motor may be actuated intermittently at the ends of the table stroke, operative connections between the second pilot valve and the fluid motor vane whereby movement of the motor vane actuates said second pilot valve continuously to operate said motor, and a control valve whereby one of the pilot valves is rendered inoperative while the other is rendered operative.

4. In a grinding machine having a longitudinally movable rotatable work support and a transversely movable rotatable grinding wheel, means including a reversing lever to reciprocate said table longitudinally, a wheel feeding mechanism including a nut and screw operatively connected to move said wheel transversely, a pawl and ratchet to rotate said screw, a vane-type fluid motor including a single rotatable vane to oscillate said pawl, a fluid actuated reversing valve associated with said motor, a pair of independent pilot valves each of which is connected to the ends of said reversing valve, operative connections between said reversing lever and one of said pilot valves whereby the pilot valve, the reversing valve and the fluid motor may be actuated intermittently to feed the grinding wheel transversely at the ends of the table stroke, operative connections between the second pilot valve and the fluid motor vane whereby the motor actuates the second pilot valve continuously to operate said motor to produce a plunge-cut infeeding movement, and a manually operable selector valve whereby one of the pilot valves is rendered operative while the other pilot valve is rendered inoperative.

5. In a grinding machine having a longitudinally movable rotatable work support and a transversely movable rotatable grinding wheel, a traverse mechanism to reciprocate said work support longitudinally, a wheel feeding mechanism to move said wheel transversely, a fluid motor operatively connected to actuate said feeding mechanism, a reversing valve associated with said motor, a pair of independent pilot valves each operatively connected to actuate said reversing valve, operative connections between the traverse mechanism and one of said pilot valves whereby the motor may be actuated intermit-

tently at the ends of the table stroke, operative connections between the second pilot valve and the fluid motor whereby the motor may be actuated continuously, and a combined selector and speed control valve whereby either of said pilot valves may be rendered operative and whereby the speed of the motor may be varied during either continuous or intermittent operation.

6. In a grinding machine having a longitudinally movable table, a rotatable work support thereon and a transversely movable rotatable grinding wheel, means including a reversing lever to reciprocate said work table longitudinally, a wheel feeding mechanism operatively connected to move said wheel transversely, a fluid motor to actuate said feeding mechanism, a reversing valve to change the direction of movement of said motor, a pair of independent pilot valves each operatively connected to shift said reversing valve in either direction, operative connections between the table reversing lever and one of the pilot valves whereby the motor may be actuated to produce an infeeding movement of the grinding wheel intermittently at the ends of the table stroke, operative connections between the second pilot valve and the fluid motor whereby the motor actuates the second pilot valve continuously to operate said motor to produce a continuous infeed or plunge-cut, and a combined selector and speed control valve whereby either of said pilot valves may be rendered operative and whereby the speed of the motor may be varied during either continuous or intermittent operation.

7. In a grinding machine having a longitudinally movable rotatable work support and a transversely movable rotatable grinding wheel, means including a reversing lever to reciprocate the table longitudinally, a wheel feeding mechanism including a nut and screw mechanism operatively connected to move said wheel transversely, a pawl and ratchet to rotate said screw, a vane-type motor including a single rotatable vane to oscillate said pawl, a fluid-actuated, shuttle-type reversing valve to control the admission to and exhaust of fluid from said motor, a fluid chamber in each end of said reversing valve, a pair of independent pilot valves each of which is connected to admit fluid under pressure to the end chambers of said reversing valve, operative connections between the reversing lever and one of said pilot valves whereby the fluid motor may be actuated intermittently to feed the grinding wheel transversely at the ends of the table stroke, operative connections whereby rotation of the fluid motor vane serves to actuate the other of said pilot valves so as to feed said wheel continuously for a plunge-cut grinding operation, and a manually operable control valve whereby one of the pilot valves is rendered operative while the other remains inoperative.

WALLACE H. WOOD.
